(57) **CLAIM**

The ornamental design for seat mechanism, as shown and described.

DESCRIPTION

1. Seat mechanism

The model is a mechanism for a chair or an armchair; **1.1** is a bottom perspective view; **1.2** is a front perspective view; **1.3** is a top perspective view; **1.4** is a right side view; **1.5** is a left side view; **1.6** is a front view; **1.7** is a rear view; **1.8** is a bottom plan view.

In the drawings, the broken lines illustrate portions of the seat mechanism that form no part of the claimed design.
